Nelson M. Howard

UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

SURFACE-SCOURING MACHINE.

1,374,194.

Specification of Letters Patent. Patented Apr. 12, 1921.

Application filed August 4, 1919. Serial No. 315,085.

To all whom it may concern:

Be it known that I, FREDERICK M. FURBER, a citizen of the United States, residing at Revere, in the county of Suffolk and State 5 of Massachusetts, have invented certain Improvements in Surface-Scouring Machines, of which the following description, in connection with the accompanying drawings, is a specification, like reference characters 10 on the drawings indicating like parts in the several figures.

This invention relates to abrading machines. The invention is set forth with particular reference to use in connection 15 with mechanisms for removing the glaze from rubber soles to prepare their surfaces for the adhesive connection of rubber heels thereto.

In the manufacture of that type of rubber 20 shoes the heels of which are molded separately from the soles, cement is used to connect the soles and heels. To enable the cement to be effective the surfaces to be connected together need to be scoured or 25 abraded to remove the glaze which results from the vulcanizing in molds. For this purpose the entire surface of the heel can well be abraded, but it is not desirable to abrade any more of the sole surface than 30 that which is to form the heel seat and will be covered by the heel.

An important object of the present invention is to provide a machine by means of which that portion of a sole to which a heel 35 is to be cemented can be roughened along a predetermined lengthwise area of the sole, to remove the glaze therefrom.

In a preferred form of the invention the machine includes a work support having an 40 adjustable gage or stop for the heel end of a sole and an abrasive roll between which and said support the sole can be drawn.

Preferably, and in accordance with another feature of my invention, a supporting 45 roll is provided below the abrasive roll, and one of said rolls is movable by the operator to vary the space between the rolls to facilitate the introduction of a sole to bear against the gage or stop and to then insure proper 50 pressure on the sole while it is being withdrawn.

Another important object is to provide a machine having an abrader and a support capable of yielding relative movements to

provide for varying inequalities in a sole 55 drawn between them, and having means whereby the operator can vary the space between the abrader and support. In the present exemplification of the invention the machine embodies an abrading roll, and a 60 coacting yieldingly mounted work support, the latter being shiftable by the operator to increase the space between the roll and support without affecting the action of the means for permitting the support to yield. 65

Other features and advantages incident to and resulting from the use of the machine will be explained in the following description in connection with the accompanying drawings, and the scope of the invention 70 will be pointed out in the appended claims.

In the accompanying drawings,

Figure 1 is a broken side elevation of a scouring machine embodying my improvement; 75

Fig. 2 is a front elevation of the upper parts of the machine looking from the right in Fig. 1;

Fig. 3 is a view similar to a portion of Fig. 1 but showing a position which the 80 work support assumes during the operation of abrading a sole; and

Fig. 4 is a detail perspective view of portions which control the movements of the work support.

A suitable column or machine frame is indicated at 12 having bearings 13 for a shaft 14 which is rotated in the direction of the arrow in Fig. 1 by any suitable means such as a pulley and belt not shown. 85

The shaft 14 projects from the frame and has secured thereto an abrasive roll 15. The support for the work, such as a sole indicated at *a* in Fig. 3, comprises a table and a roll connected thereto between which roll 95 and the abrasive roll the work is to be drawn. This work support also serves the purpose of a gage carrier. In the particular embodiment of the invention illustrated this portion of the machine comprises a 100 table 16 having a work gage or stop 17 adjustable toward or from the nip or bite of the rolls and secured in position by a screw 18. Said table or gage carrier is carried at the upper end of yoke or frame 19 the lower 105 end of which (Fig. 2) is formed as a sleeve 20 (Fig. 2). This sleeve is secured to a pin 21 by means of a set screw 22. Mounted in

an opening of the yoke or frame 19 is a pressure roll 23 mounted loosely on a pin or shaft 24.

A bracket portion 25 of the frame, as best shown in Fig. 4, has a sleeve 26 at its lower end. Extending through and fixed in said sleeve is a pin 27. Mounted to rock on the pin 27 is a hub 28 having arms 29 formed or provided with bearings for the pivot pin 21 hereinbefore described. Another arm 30 of said hub 28 is connected by a link 31 to a foot lever 32.

To normally hold the parts in the position shown in Fig. 1 a spring 33 is employed, attached at one end 34 to the column or frame of the machine and at its other end to an arm 35 of the sleeve 20 (Figs. 1 and 2).

A spring 36 is attached at one end to the table or gage carrier 16 and at the other end to the frame of the machine. This spring 36 exerts a constant tendency to move the yoke or frame 19 in a somewhat angular direction on pivot 21, such movement, however, being limited by a roll 37 loosely mounted on pin 24 and bearing against a guide 38 projecting from the frame bracket 25 (Fig. 4). The hub 28 has a lug 39 in which a screw 40 is mounted, the inner end of said screw being adapted to contact with a stop lug 41 of the fixed bearing 26.

Normally the parts of the machine occupy the relative positions shown in Fig. 1. When a sole *a* is to be abraded, it is inserted to the position indicated by dotted lines in Fig. 1, with its glazed surface uppermost. The operator then, by depressing the foot lever 32, actuates the lever 30, 29, to raise the pin 21 and through the latter shift the table and roll carrying frame 19 to or toward the position shown in Fig. 3. He then immediately withdraws the sole and, owing to the direction of rotation of the abrasive roll being as indicated by the arrow, the upper surface of the sole is roughened. The longitudinal extent of action on the sole depends, of course, on how far the sole is inserted before the normal space between the abrasive roll and the work support has been reduced. This distance of insertion is regulatable by adjusting the gage or stop 17. Of course said gage or stop might be entirely omitted and then there would be no interference with using the machine for roughening an unlimited area of the sole which may be run through twice, once with one end first and then, reversing the sole, with the other end first.

The spring 36 serves the purpose of rendering the table or work support yieldable at all times whether the latter has been fully raised by the operator or not. In other words, after the table has been raised to the limit determined by the adjustable stop

sole will still be taken care of because said spring 36 permits the support to yield.

By comparing Figs. 1 and 3 it will be readily understood that by adjusting the screw 40, the degree to which the space between the abrasive roll and the work support can be reduced by depressing the foot lever 32 can be varied to suit the thickness of the work to be operated upon, without risk of actual contact of the abrasive roll 75 and the work support when there is no work between them. This will be understood readily by referring to Fig. 3 which shows that with the screw 40 nearly in contact with stop lug 41, the frame 19 and its roll 23 can only be lifted, by the spring 36, from the full line position to the dotted line position even after the sole has been entirely withdrawn. In other words, supposing that the screw 40 has been adjusted to the position shown in Figs. 1 and 3, the parts of the machine normally stand as in Fig. 1 and the work can be freely inserted against the stop 17. If the work is of the thickness represented, or if a thin portion should be 90 between the two rolls, the spring 36 would yieldingly tend to maintain the table and roll in substantially the position indicated by dotted lines in Fig. 3, the end of screw 40 then contacting with lug 41. A thick 95 sole, or a thicker portion of the sole, would simply act to depress the roll 23 and table 16 to, say, substantially the full line position of Fig. 3. After the sole is entirely withdrawn, assuming that the lever 29, 30, 100 is still held in the position of Fig. 3, there can be no contact of roll 23 with roll 15 because of the limiting effect of screw 40 and stop 41.

Having described my invention, what I 105 claim as new is:

1. A machine for scouring rubber soles, comprising an abrading roll, a movable support opposite said roll, means carried by said movable support to determine the initial position of the work, and means to rotate the abrading roll in a direction to oppose the withdrawal of the work. 110

2. A machine for scouring rubber soles, comprising an abrading roll, a support opposite said roll and including a loosely mounted presser roll, means to determine the initial position of the work, and means to rotate the abrading roll in a direction to oppose the withdrawal of the work. 115

3. A machine for scouring rubber soles, comprising an abrading roll, a presser roll on which the sole is supported, initial setting means at one side of the rolls to engage one end of a sole to cause its other end to project from the other side of the rolls, and means to move the presser roll to carry the sole against the abrading roll when the sole is withdrawn. 125

4. In a machine of the character described. 130

- an abrading roll and a sole support one of which is mounted to yield relatively to the other, said support comprising a table and a roll, and means for manually varying the 5 space between the abrading roll and support without materially affecting the pressure on a sole passed between the abrading roll and support.
5. In a machine of the character described, 10 an abrading roll and a sole support one of which is mounted to yield relatively to the other, said support comprising a table having a gage and a roll connected with the table, and means for manually varying 15 the space between the abrading roll and support without materially affecting the pressure on a sole passed between the abrading roll and support.
6. A machine of the character described, 20 having, in combination, an abrasive roll, a pressure roll, means for normally holding the rolls yieldingly separated, and means for manually reducing the space between the rolls.
- 25 7. A machine of the character described, having, in combination, an abrasive roll, a pressure roll, means for normally holding the rolls yieldingly separated, a foot treadle, and connections whereby actuation of 30 said treadle will reduce the space between the rolls.
8. A machine of the character described, 35 having, in combination, an abrasive roll, a pressure roll, means for normally holding the rolls yieldingly separated, an adjustable gage for determining the distance to which work can be inserted between the rolls, and means for manually reducing the space between the rolls.
- 40 9. A machine of the character described, having, in combination, an abrasive roll, a movable frame carrying a work support and a gage, means for normally holding said frame yieldingly in a lowered position, 45 and means for manually raising said frame.
10. A machine of the character described, having, in combination, an abrasive roll, a
- pivottally supported frame carrying a pressure roll, means for varying the position of the pivot of the frame, and means for guiding the frame relatively to the abrasive roll when said pivot is shifted. 50
11. A machine of the character described, having, in combination, an abrasive roll, a pivottally supported frame carrying a pressure roll, means for varying the position of the pivot of the frame, and means for guiding the frame relatively to the abrasive roll when said pivot is shifted, said guiding means comprising a roller in axial alignment with the pressure roll and a fixed track for said roller. 55
12. A machine of the character described, having, in combination, an abrasive roll, a pivottally supported frame carrying a pressure roll, means for varying the position of the pivot of the frame yieldingly in one direction and positively in the opposite direction, and means for guiding the frame relatively to the abrasive roll when said pivot 60 is shifted. 65
13. A machine of the character described, having, in combination, an abrasive roll, a pressure roll, means for normally holding the pressure roll yieldingly separated from the abrasive roll, means for manually shifting the pressure roll toward the abrasive roll, and means for adjustably limiting the point to which said pressure roll can be shifted. 70 75
14. A machine of the character described, having, in combination, an abrasive roll, a pressure roll, means for normally holding the pressure roll yieldingly separated from the abrasive roll, means for manually shifting the pressure roll toward the abrasive roll, and means for adjustably limiting the point to which said pressure roll can be shifted, said limiting means comprising a fixed stop and a coöperating adjusting 80 85 screw connected to the pressure roll carrier. 90

In testimony whereof I have signed my name to this specification.

FREDERICK M. FURBER.
